RIBBON FEED MECHANISM

Ludwick Szehiga, Wapping, Conn., assignor to Royal McBee Corporation, New York, N.Y., a corporation of New York

Filed Apr. 5, 1963, Ser. No. 271,001
8 Claims. (Cl. 197—151)

This invention relates to an improved ribbon feed mechanism for a power operated typewriter and more particularly to a selectively operable fabric or carbon ribbon feed mechanism capable of automatic reversal during fabric ribbon feed.

To increase their versatility modern electric typewriters are capable of using fabric or carbon ribbon and are provided with feed mechanisms therefor. It has been proposed (see U.S. Patents 1,722,937, 2,616,547 and 3,038,582) to power the fabric ribbon feed and/or the ribbon feed reverse mechanism from the power roll rather than the carriage drive spring barrel, but these proposals do not provide for selective fabric or carbon ribbon feed driven from a common source of power other than the spring barrel or a type bar linkage.

It is accordingly among the objects of this invention to provide a simple and reliable fabric or carbon feed mechanism that is selectively operable to be driven from a common drive shaft powered by the typewriter power roll to feed fabric or carbon ribbon and to operate the fabric ribbon reversing mechanism. Other objects will be in part apparent and in part pointed out hereinafter.

In accordance with my invention the mechanism includes a universal bar that is operative in response to depression of any alpha-numerical key lever to trigger a roll cam into engagement with the power roll. As the cam is driven it rocks a lever on which it is mounted to engage a wrap spring clutch between the lever and a drive shaft whereby such shaft is intermittently driven by successive triggering of the roll cam. This drive shaft is, in turn, selectively connectable with the fabric ribbon spool spindles and a carbon ribbon feed mechanism whereby either fabric or carbon ribbon is optionally employable. Conventional fabric ribbon reversing mechanism is employed but is operated by the roll cam lever rather than in the conventional manner.

In the drawing wherein I have shown a preferred embodiment of the invention and wherein similar reference characters refer to similar parts throughout the several views.

FIGURE 1 is an enlarged fragmentary elevation of the mechanism (the fabric ribbon feed and reversing portions) looking from the inside of the typewriter toward the left hand side thereof and taken along the line 1—1 of FIGURE 2;

FIGURE 1A is an enlarged elevation showing another fragment of the mechanism (the common drive for fabric or carbon ribbon feed) viewed in the same direction as the fragment of FIGURE 1, the common line X—X in FIGURES 1 and 1A indicating the center line of common portions of the two fragments;

FIGURE 2 is a reduced fragmentary front elevation of the mechanism;

FIGURE 3 is a reduced exploded isometric view of portions of the mechanism shown in FIGURES 1 and 2; and

FIGURE 4 is a fragmentary elevation of a portion of the mechanism shown in FIGURE 2.

Ribbon drive mechanism

Referring first to FIGURE 1A, the drive mechanism for the fabric and carbon feed is generally indicated at 10 and comprises a number of elements which, for the most part, are mounted on a bracket generally indicated at 11 having an outer side plate 11a adapted to be secured to

2

the side frame F of the typewriter in any suitable manner. The bracket also includes an inner side plate 11b and a back plate 11c, the several plates preferably being integral and so disposed that the bracket is U-shaped in horizontal section. A drive shaft 12 is rotatably mounted in plates 11a and 11b and is constrained to counterclockwise movement only in a manner and for a purpose described below. A U-shaped drive lever generally indicated at 13 (see also FIGURE 3) comprises sides 13a and 13b integrally connected by a top bar 13c, the lever being rockably mounted on shaft 12, which extends through sides 13a and 13b thereof, and being biased clockwise by a spring 14 connected at one end to an ear 13d on the lever and a lug 11d on bracket 11. A wrapped spring drive clutch 15 is wound around shaft 12, has one end 15a connected to a pin 13e on lever side 13b, and is so coiled as to engage shaft 12 and drive it counterclockwise when lever 13 is rocked counterclockwise during its drive stroke and as to disengage upon clockwise rocking of the lever on its return stroke. To preclude clockwise rotation of shaft 12 during the return stroke of the lever, a no-back wrapped spring clutch 16 is wound on shaft 12, has one end 16a fastened to a pin 17 fastened to bracket side 11b and is so coiled as to prevent such clockwise rotation of shaft 12. It may now be seen that as drive lever 13 is oscillated (as will be described) drive shaft 12 is intermittently driven but counterclockwise only.

A drive pin 18 is mounted on the end of lever side 13b and is embraced by the bifurcated end 19a of one arm 19b of a bell crank 19 pivotally mounted on a stud shaft 20 carried by the machine frame. The other arm 19c of bell crank 19 has a roll cam 21 eccentrically mounted thereon as by a pin 22, the cam carrying a stud 21a which anchors one end of a return spring 23 whose other end is fastened to a lug 19d comprising an integral portion of bell crank 19. Cam 21 is located adjacent a power roll 24, rotatably mounted and driven in conventional manner, and is adapted to engage the power roll when the mechanism is triggered by depression of an alpha-numerical key as will now be described.

Actuation ribbon drive mechanism

Still referring to FIGURES 1A and 3, the free end of bracket side 11b carries a pin 25 on which a trigger generally indicated at 26 is rockably mounted. The trigger includes an actuating bar 26a and a hooked trip arm 26b adapted to hold and release a pin 27 mounted through the end of lever side 13a, a spring 28 being interconnected to bar 26a and bracket lug 11d to bias the trigger counterclockwise to its holding position shown in FIGURE 1A. A conventional universal bar 29 is pivotally connected to bracket side 11b and is adapted to be rocked clockwise by a typical key sub-lever 95 (comprising an element of one of several type bar operating power units which may resemble that shown in said Patent 2,616,547), upon depression of the key (not shown) associated with the sub-lever, against trigger bar 26a to rock trigger 26 clockwise. When the trigger is so rocked its hook arm 26b releases pin 27 permitting spring 14 to rock lever 13 clockwise forcing pin 18 upwardly to rock bell crank 19 clockwise thus to engage roll cam 21 with power roll 24. Because of the eccentricity of cam 21 its engagement with the power roll results in bell crank 19 being driven counterclockwise. In practice when the cam 21 has rotated about 150 degrees, the bell crank has been given its maximum counterclockwise movement. It should be noted that the 150 degree rotation of the cam is illustrative only, the degree of rotation thereof depending on the design of the cam and other geometrical considerations of no relevance here.

As bell crank 19 rocks counterclockwise, its bifurcated end 19a drives lever drive pin 18 downwardly thus rocking lever 13 counterclockwise to rotate shaft 12 counter-

clockwise as described above. After the bell crank reaches its maximum downward swing, spring 14 acting through lever 13 and pin 18 returns the bell crank to its normal, i.e. inactive FIGURE 1A position. It should also be noted that in the meantime, universal bar 29 has returned to its rest position and spring 28 has rehooked trigger arm 26b over pin 27.

It will now appear that repeated release operation of trigger 26 by successive key depressions results in intermittent counterclockwise actuation of drive shaft 12, it now being noted that this shaft is a power output shaft common to both the fabric ribbon and carbon ribbon feed mechanisms and is driven by the power roll of the typewriter.

Fabric ribbon feed mechanism

As shown in FIGURE 2, drive shaft 12 carries a spur gear 30 which meshes with a gear 31 mounted on a pin 32 for both rotational and axial movement relative thereto, the pin being secured to the machine side frame F and carrying an expansion spring 33 between the hub of gear 31 and a washer 34 on the end of the pin. The spring yieldably biases gear 31 to the left to mesh with gear 30 but permits out-of-mesh movement of gear 31 to the right for a purpose to be described.

The fabric ribbon feed mechanism assembly is generally indicated at 40 (FIGURE 2) most of the elements thereof being mounted on a bracket generally indicated at 41 (FIGURE 2). This bracket includes a main mounting plate 41a by which the entire assembly 40 is suitably secured to machine frame F. The bracket includes upper and lower horizontal mounting plates 41b and 41c which rotatably support a fabric ribbon spool spindle 42, plate 41b also providing a support for a ribbon spool cut 43 adapted to receive a fabric ribbon spool 44. This spool may be similar to that shown in U.S. Patent 2,880,841, and accordingly includes a reversing cam 44a that moves to the dotted line position (FIGURE 1) when the ribbon is substantially unwound from the spool 44 to effect reverse ribbon feed as will be described below. The upper end of spindle 42 is drivingly received in the core of spool 44 and its lower end has a bevel gear 45 attached thereto.

A tab 41d (FIGURE 2) extends downwardly from plate 41c and rotatably supports one end 46a of a cross shaft 46 and the other end 46b of which is journaled in a bracket 47 suitably mounted on the machine frame. Shaft end 46a has mounted thereon a pinion 48 that is in constant mesh with gear 31 and a bevel gear 49 that is adapted to mesh with bevel gear 45 in one condition of operation and being out of mesh therewith in another condition of operation as will be described below.

Cross shaft end 46b carries a bevel gear 50 meshable with a bevel gear 51 secured to the lower end of ribbon spool spindle 52 journaled in bracket 47. This spindle is similar to spindle 42 and its upper end is received in a ribbon spool 53 similar to spool 44 and accordingly being provided with a reversing cam 53a. Cross shaft 46 also carries a collar 54 between which and tab 41d an expansion spring 55 is disposed, this spring yieldably biasing the cross shaft to the right as viewed in FIGURE 2 to cause bevel gears 50 and 51 to mesh.

It may now be seen that when drive shaft 12 is driven as described above, its gear 30 drives gear 31 to drive pinion 48 and accordingly cross shaft 46. Depending upon which of the sets of bevel gears 45 and 49 or 50 and 51 are in mesh spindle 42 or 52 is driven thus to feed ribbon from spool 44 or 53, the driven spool being the take-up spool and the idling spool being the supply spool.

Fabric ribbon reversing mechanism

The mechanism for automatically reversing the direction of fabric ribbon feed is actuated by the pin 27 (FIGURES 1A and 3) on lever side 13a, the location of the driving connection between this pin and the reversing mechanism being indicated by the line X-X in FIG-

URES 1 and 1A. Bracket 41 (FIGURE 1) includes a flange 41e lying in a plane parallel to plate 41a to which it is integrally joined by a side plate 41f. A lower flange 41g is also integral with side plate 41f and is coplanar with upper flange 41e. A reversing lever, generally indicated at 60, is pivotally mounted on flange 41e and is biased counterclockwise by a spring 61 connected between the lever and flange 41e. This lever, at its upper end, includes an arcuate laterally projecting cam 60a which lies in the path of travel of the foot 44b on reversing cam 44a so as to be engaged thereby when the ribbon on spool 44 is sufficiently unwound therefrom to release cam 44a and permit it to rock into the dotted line position shown in FIGURE 1. For a more detailed description of this structure and its operation reference is made to said U.S. Patent 3,038,582. When lever 60 is so engaged it is rocked clockwise (FIGURE 1) against the bias of the return spring 61.

Lever 60 (see also FIGURE 3) includes a lug 69 to which is riveted a downwardly extending resilient leg 62 adapted to yieldingly bear against a lobe 63a formed on an actuator generally indicated at 63. This actuator includes a hook 63b and a stop 63c and also includes an arm 63d which is pivotally connected as by a pin 65 (FIGURE 1) to the upper end 66a of a bell crank lever 66 in turn pivotally mounted on lower flange 41g by a pin 67. A spring 64 interconnects bell crank 66 and bracket wall 41f to yieldingly bias the bell crank counterclockwise, such movement being limited by a stop 66b on the bell crank engaging bracket plate 41c. Bell crank 66 includes a lug 66c which anchors one end of a spring 68 the other end of which is connected to actuator stop 63c thus to yieldably bias the actuator 63 counterclockwise to the extent of the engagement of its stop 63c against the edge of bell crank 66. A cam 69 is integrally formed on the lower end of the bell crank and includes a cam surface 69a (FIGURE 3) which is adapted to engage the hub 48a of pinion 48 when the bell crank is rocked clockwise in a manner to be described. When the pinion hub is so engaged pinion 48 and accordingly cross shaft 46 are shifted to the left (FIGURE 2) against the push of spring 55 causing bevel gears 49 and 45 to mesh and bevels 50 and 51 to unmesh thus reversing the ribbon spool drive as described in detail in said U.S. Patent 3,038,582.

In order to hold the several gears in this position shaft 46 has a collar 70 fastened thereto against which a detent arm 71 is adapted to rest when the parts are in their FIGURE 2 position. This arm comprises the lower end of a link 72 pivotally mounted on the machine frame as at 73, the upper end of this link carrying a cam 74, similar in construction and operation to cam 60a, which coacts with reversing cam 53a on spool 53. Thus when shaft 46 is shifted to the left (FIGURE 2) as described above to reverse the ribbon feed, collar 70 shifts with the shaft to the left of arm 71 which, from the bias of a spring 72a, swings toward and against shaft 46 adjacent the right hand side of collar 70 to hold the shaft and bevel gears in their shifted (reverse feed) position.

In view of the foregoing it may now be seen that fabric ribbon reversal results as follows. With the parts in their solid line positions (FIGURES 1 and 2) ribbon is being unwound from spool 44 and is being taken up on spool 53. When sufficient ribbon has been taken off spool 44 to release reversing cam 44a (FIGURE 1) it drops to its broken line position where it will intercept cam 60a and in so doing rock lever 60 clockwise to its broken line position causing resilient arm 62 to press against actuator lobe 63a to rock actuator 63 clockwise. This positions actuator hook 63b in the path of travel of pin 27 on lever side 13a so that on the downward stroke of lever 13 by virtue of operation of drive shaft 12 as described above pin 27 travels downwardly from its FIGURE 1 broken line position to engage hook 63b and thus rock actuator 63 clockwise. This movement is imparted to bell crank 66 which accordingly also rocks clockwise

to swing cam 69 against pinion hub 48a causing shaft 46 to shift to the left (FIGURE 2). This results in meshing of bevels 45 and 49 and unmeshing of bevels 50 and 51 thus to reverse the ribbon take-up action from spool 53 to spool 44. When the ribbon is substantially unwound from spool 53, its cam lever 53a forces arm 71 away from shaft 46 and clear of collar 70 so that spring 55 is enabled to shift shaft 46 thus to re-engage bevels 50 and 51 and disengage bevels 45 and 49 so that the ribbon feed is again reversed, i.e. spool 44 again becomes the take-up spool. 10

Carbon ribbon feed mechanism

This mechanism does not include any ribbon reversing means as carbon ribbon is used but once and is then discarded. Common drive shaft 12, as noted above, also operates the carbon ribbon mechanism. With reference to FIGURES 2 and 4, the left hand end of shaft 12 has a carbon ribbon feed roll 80 secured thereto. The shaft end also carries a pulley 81, a friction disc 82 being disposed between this pulley and bracket plate 41. An expansion spring 83 is coiled around shaft 12 between roll 80 and pulley 81 to force the pulley against the friction disc for a purpose to be described. 15

A pressure roll 84 is rotatably mounted on a stub shaft 85 secured to an arm 86 (FIGURE 1A) pivotally mounted on the machine frame in any suitable manner. Arm 86 includes a leg 86a to which one end of a spring 87 is fastened, the other spring end being fastened to the frame thus to yieldably bias arm 86 counterclockwise so that pressure roll 84 and feed roll 80 may grip the carbon ribbon. Thus rotation of shaft 12 rotates feed roll 80 to feed carbon ribbon. 20

A take-up spool 88 (FIGURE 2) is rotatably mounted on frame F and includes a pulley 88a. A belt 89 is trained around pulleys 81 and 88a whereby the former drives the latter and accordingly spool 88. The friction disc 82 referred to above permits slippage of pulley 81 on shaft 12 to accommodate the increasing amount of used ribbon wound on spool 88. 30

When fabric ribbon is being used it is desirable to disable the carbon ribbon feed mechanism. To this end a lever generally indicated at 90 (see also FIGURE 4) is pivotally mounted on a pin 91 secured to slide plate 41f of bracket 41 and includes a handle 90a, a shifting foot 90b, and a pulley lock 90c. When lever 90 is pivoted clockwise, as viewed in FIGURE 4, lock 90c thereon enters one of several notches 81a formed in pulley 81 so that the shaft 12 slips in the pulley when the shaft is rotated. A lug 90d comprises an integral part of lever 90 and underlies a lip 86b comprising a portion of pressure roll arm 86. When lever 90 is pivoted as described lug 90d engages lip 86b to rock arm 86 clockwise thus to move the pressure roll 84 upwardly away from carbon ribbon feed roll 80 thus disabling the carbon ribbon feed mechanism. By the same token when carbon ribbon is being used it is desirable to disable the fabric ribbon feed mechanism. Shifting foot 90b on lever 90 is provided for this purpose. This foot is disposed adjacent gear 31. Thus when lever 90 is pivoted counterclockwise, its foot 90b engages the side of gear 31 and forces it to the right (FIGURE 2) against the pressure of spring 33 until it is unmeshed from gear 30 thus disabling the drive to the fabric ribbon feed mechanism. A pair of detent slots 41h are formed in bracket 41 to receive the upper end 90a of lever 90 thus to hold it in either of its operative positions. 45

In order to condition the above described mechanism for cutting a stencil it is desirable to disable shaft 12 so that neither the fabric nor carbon ribbon feed mechanisms will be driven. To this end an arm 92 (FIGURE 1A) is pivotally mounted on the machine frame in any suitable manner and includes a finger 92a adapted to be swung behind lever 13 when the arm 92 is appropriately 50

pivoted. With the finger so positioned lever 13 will not rock upon operation of trigger 26 as described and accordingly shaft 12 will not be driven. Hence a stencil may be cut without any ribbon being fed. 55

It may now be seen that I have provided a power driven fabric or carbon ribbon feed mechanism that attains the several objects set forth above in a thoroughly practical and efficient manner.

I claim:

1. In a power driven typewriter having a power roll, a plurality of actuatable key sub-levers and a universal bar adapted to be operated by an actuated sub-lever, the combination of, mechanism for feeding fabric ribbon, mechanism for feeding carbon ribbon, a common drive shaft, means to selectively couple said shaft to said mechanisms for operating one or the other of them, and means driven by said power roll and responsive to operation of said universal bar for driving said common drive shaft.
2. Apparatus according to claim 1 including manually operable means to disable said common drive to preclude operation of either of said mechanisms.
3. Apparatus according to claim 1 wherein said fabric ribbon feeding mechanism includes a rotatable shaft, a train of gears forming a driving connection between said shafts, and means mounting one of the gears of said train for axial movement into and out of mesh with at least one other gear of said train whereby said fabric ribbon feeding mechanism shaft may be coupled to or uncoupled from said common drive shaft.
4. Apparatus according to claim 1 wherein said carbon ribbon feed mechanism includes a drive pulley frictionally connected to said common shaft, and means to restrain rotation of said pulley when said shaft is coupled to said fabric ribbon feeding mechanism.
5. Apparatus according to claim 1 wherein said fabric ribbon feeding mechanism includes a rotatable shaft and said carbon ribbon feeding mechanism includes a drive pulley frictionally connected to said common shaft, and manually operable means to couple said common drive shaft to said fabric ribbon feeding mechanism shaft and at the same time restrain operation of said pulley thereby to enable said fabric ribbon feeding mechanism and disable said carbon ribbon feeding mechanism.
6. Apparatus according to claim 5 including manually operable means associated with said power roll driven means to disable both of said ribbon feeding mechanisms to enable cutting of a stencil without any ribbon feed.
7. Apparatus according to claim 1 wherein said second mentioned means includes an oscillatable lever mounted on said shaft, and clutch means engageable upon operation of said universal bar to connect said lever to said shaft whereby said shaft is operated every time said universal bar is operated.
8. Apparatus according to claim 7 including means operated by said power roll to oscillate said oscillatable lever.
